UNITED STATES PATENT OFFICE.

THOMAS F. McCORMICK, OF ST. PAUL, MINNESOTA.

DESIGN FOR A TEA OR COFFEE CAN.

SPECIFICATION forming part of Design No. 30,878, dated May 30, 1899.

Application filed May 1, 1899. Serial No. 715,260. Term of patent 14 years.

To all whom it may concern:

Be it known that I, THOMAS F. McCORMICK, a citizen of the United States, residing at St. Paul, county of Ramsey, State of Minnesota, have invented a new and original Design for Tea or Coffee Cans, of which the following is a specification, reference being had to the accompanying drawing, which is a perspective view of a can embodying my design.

- 5 As shown in the drawing, the can is rectangular in outline, with the corners between the front and sides cut away to form narrow faces or panels 5. The top 2 of the can is inclined, such inclined portion being separated from the rear side of the can by a narrow horizontal portion 3. A cover 4 is hinged in the inclined top some distance below the horizontal portion 3 and projects beyond the front edge of the can. The cover in width is less than the width of the can, with the cover-hinge extending entirely across the top of the can. The relative proportions of the different faces as well as the arrangement of the

cover with its projecting edge are essential features of my design. It will be seen that 25 the width of the can is considerably greater than the depth and that the height of the can is much greater than the width. The faces or panels 5 between the front and sides are comparatively narrow. The horizontal 30 top portion 3 is also very narrow, and the space between the top portion and the hinge of the cover is greater than the width of such top portion.

Having described my invention, what I 35 claim as new, and desire to secure by Letters Patent, is—

The design for a tea or coffee can; substantially as herein shown and described.

In testimony whereof I affix my signature 40 in the presence of two witnesses.

THOMAS F. McCORMICK.
